UNITED STATES PATENT OFFICE

97,822

DESIGN FOR A TEXTILE FABRIC

Joseph W. Powdrell, Wellfleet, Mass., assignor to Powdrell & Alexander, Inc., Danielson, Conn., a corporation of Massachusetts

Application October 18, 1935, Serial No. 59,107

Term of patent 3½ years

To all whom it may concern:

Be it known that I, Joseph W. Powdrell, a citizen of the United States, residing at Wellfleet, in the county of Barnstable, State of Massachusetts, have invented a new, original, and ornamental Design for Textile Fabrics, of which the following is a specification, reference being had therein to the accompanying drawing.

The drawing is a face view of a portion of the fabric, showing my new design.

I claim:

The ornamental design for textile fabric, substantially as shown.

JOSEPH W. POWDRELL.
